United States Patent Office

Des. 210,899
Patented Apr. 30, 1968

210,899

PLATE OR THE LIKE

Ottorino N. Mercadante, Corning, N.Y., assignor to Corning Glass Works, Corning, N.Y., a corporation of New York

Filed Oct. 2, 1967, Ser. No. 8,835

Term of patent 14 years

(Cl. D44—15)

The figure is a top plan view of a plate of conventional configuration showing my new design.

I claim:

The ornamental design for a plate or the like, as shown and described.
